Specification for Design.

Patented Dec. 14, 1915.

Application filed August 13, 1914. Serial No. 856,690. Term of patent 3½ years.

To all whom it may concern:

Be it known that I, JOHN BOHNET, a citizen of the United States, residing at Lansing, in the county of Ingham and State of Michigan, have invented a new, original, and ornamental Design for Automobile Tops, of which the following is a specification, reference being had to the accompanying drawing, forming part thereof.

In the drawing, Figure 1 is a side view of my improved design for automobile tops. Fig. 2 is a rear view of my improved design.

In my improved design the lower edge of the top is curved to conform to the shape of the upper edge of the automobile body on which it is designed to be placed.

I claim as my invention and desire to secure by Letters Patent:

The ornamental design for an automobile top, as shown.

JOHN BOHNET.
